MOTOR DRIVEN LINEN POUNDER

Paul Schulz, Magdeburg, Germany

Application August 30, 1934, Serial No. 742,156
In Germany January 9, 1933

1 Claim. (Cl. 68—5)

This invention relates to a linen pounder with bell operated by an electric motor. Linen pounders and washing devices with an inner bell actuated by an electric motor are known. As compared with these arrangements the casing enclosing the motor and gearing in the linen pounder according to the invention is mounted on a tube, the lower end of which carries the outer bell, the tube serving as guide for the lifting rod for moving the inner bell which, in known manner, is open at the top and provided with a perforated bottom. By this novel arrangement the linen pounder is considerably simplified as compared with the known articles of this type, because the tube serves at the same time as a handle for the operator, as carrier of the motor with the gearing and as guide for the lifting rod of the inner bell. The outer bell may be moved instead of the inner bell or a rubber diaphragm may be employed instead of the inner bell.

Two embodiments of the invention are illustrated by way of example in the accompanying drawing in which:—

Fig. 1 shows in longitudinal section a linen pounder with movable inner bell.

Fig. 2 shows in longitudinal section the lower portion of a linen pounder in which a rubber diaphragm is employed instead of an inner bell.

An outer bell 2 is fixed on the lower end of a tube 1 serving as handle. An inner bell 3 is provided at its lower end (Fig. 1) with a perforated bottom. In the construction illustrated in Fig. 1 the inner bell is fixed on a lifting rod 5 which is guided in the tube 1 by piston-like guide elements 6.

The inner bell (Fig. 1) is driven by an electric motor 7 which is accommodated in a hood 8 made of insulating material and attached to the upper end of the tube 1. A worm 9 driven by the motor 7 meshes with a worm wheel 10 carrying a crank 11 hingedly connected by a con-

necting rod 12 to the upper piston 6 on the lifting rod 5.

By employing a worm wheel transmission and owing to the high speed of rotation of the motor, the number of strokes of the inner bell is reduced so far that the pounder only carries out the necessary number of movements. The motor proper is mounted on a frame 14 provided with a plug socket 15 for the plug on the lead conducting to the source of current.

In the modified form of construction illustrated in Fig. 2 the inner bell consists of a cap-shaped rubber bell or diaphragm 3', the annular outer edge 3a of which engages in a groove formed by an outwardly projecting bead 2' in which it is securely held by a spring ring 16. The rubber diaphragm 3' is held at the middle between two metal discs 17 connected by screws 18. The lifting rod 5 extends through the two discs 17 so that during the reciprocating movement of the lifting rod the discs 17 and the rubber diaphragm 3' are moved up and down.

I claim:—

A linen pounder, comprising in combination a tube, a casing on the upper end of said tube, an electric motor accommodated in said casing, an outer bell on the lower end of said tube, a lifting rod vertically guided in said tube, a gearing in said casing driven by said motor and connected with the upper end of said rod adapted to impart a vertical reciprocating movement to said rod, a cup-shaped rubber diaphragm in said outer bell, means for connecting the middle of said diaphragm with the lower end of said lifting rod, an outwardly projecting bead on said outer bell forming an annular groove in said outer bell, an edge on said diaphragm engaging in said annular groove, and a spring ring clamping said edge in said groove.
